UNITED STATES PATENT OFFICE.

WILLIAM C. DEISS, OF BROOKLYN, NEW YORK.

MOTHPROOF CHEST.

Application filed March 15, 1922. Serial No. 543,887.

To all whom it may concern:

Be it known that I, WILLIAM C. DEISS, a citizen of the United States, and a resident of the city of New York, borough of Brooklyn, in the county of Kings and State of New York, have invented a new and Improved Mothproof Chest, of which the following is a full, clear, and exact description.

This invention relates to improvements in mothproof chests, an object of the invention being to provide a device of this character in which clothing or other articles may be conveniently stored, and which may be so closed as to effectively prevent the entrance of moths, or which may be treated in such a manner as to be repugnant to moths.

A further object is to provide a device of this character, which may be conveniently collapsed for the purpose of transportation or storage.

Still another object is to provide a moth-proof chest which will be exceedingly light in weight, yet strong and durable in construction, and one which will occupy a comparatively small amount of space when collapsed, and which will be capable of economical manufacture.

With these and other objects in view, the invention consists in certain novel features of construction and combinations and arrangements of parts as will be more fully hereinafter described and pointed out in the claims.

In the accompanying drawings:

Figure 1 is a perspective view of my improved chest in closed position;

Figure 2 is another perspective view of the chest showing the same open and partially collapsed;

Figure 3 is a view in longitudinal section through the chest when the same is in open position;

Figure 4 is another longitudinal sectional view with the chest partially collapsed and taken approximately on the line 4-4 of Figure 3; and

Figure 5 is a view in transverse section showing the chest almost entirely collapsed.

Referring in detail to the drawings, I have used the reference numeral 1 to indicate a bag having a rectangular bottom. This bag is preferably of some mothproof material, or treated in such a way that it is repugnant to moths. The bag is of such a size that it conveniently accommodates a square box 2, said box fitting within and resting

on the bottom of the bag. The box may be formed of corrugated board or other suitable material which is light in weight, and yet sufficiently strong in construction to withstand the uses for which this particular box is intended.

The box proper is preferably a little more than half the height of the bag and forms in effect a stiff lining for the lower portion of the bag 1. It includes a pair of side flaps 3 adapted to fold over and cover the top of the box and these flaps are preferably adhesively or otherwise suitably connected to the inside walls of the bag. Each flap is preferably half the width of the box so that as the flaps are folded over the open top of the box the same is completely closed.

The box 2 is likewise provided with end flaps 4. These flaps are not connected to the bag and are used in connection with the flaps 3 to lend rigidity and strength to the box when in closed position. In packing the box, one or both of the flaps may be folded inwardly, as seen most clearly in Figure 3, in order to prevent the side walls of the box from buckling or breaking inwardly. The flaps thus serve the double function of strengthening the box and holding the same in open position while packing.

After the box has been packed, the flaps 3 are folded down upon the flaps 4 and the flexible free end 5 of the bag 1 is folded over upon itself, as indicated in Figure 1, and locked with a conventional type of locking hook 6. This hook forms no part of the present invention and any other suitable device might be substituted therefor. Reinforcing patches 7 may, if desired, be provided at the corners of the bag under which the hooks 6 engage.

It is hereinbefore stated that my improved moth-proof chest is capable of being collapsed so as to occupy a very small amount of space while being transported empty, or for storage purposes. This result is accomplished by providing score lines 8 in the side walls of the box. These score lines are parallel to the bottom of the box and are disposed about midway of its height. Score lines 9 extending across the ends of the box are located in the same horizontal plane with and join the score lines 8. Vertical score lines or fold lines 10 extend from the intermediate portions of the lines 9 to the top of the bag, both the body of the box and the end flaps 4 being scored. Extend-

ing from the lower ends of the score lines 10 to the lower corners of the box 2 are diagonal fold or score lines 11. The bottom of the box is not foldable.

5 The chest is collapsed from its full open position with all of the box flaps raised. Pressure upon the ends of the chest will cause the same to break inwardly on the score lines 10 and 11, as seen clearly in Figures 2 and 4. The box may then be folded laterally upon either of the lines 8, one of the side walls of the box remaining straight and the other collapsing, as seen most clearly in Figure 5. This permits the body of 15 the box to be folded over upon the box bottom in the manner shown in Figure 5 of the drawings. The score lines 9 are of course necessary in order to permit lateral folding of the box after it has been broken in at the 20 ends on the lines 10 and 11. The score lines are only necessary in the box proper since the bag will naturally fold in accordance with the way in which the box itself is folded.

25 As before stated the material from which the chest is made is not necessarily important as long as the same is moth-proof; the flaps 3 need not necessarily be attached to the bag and numerous slight changes and 30 alterations might be made in the general form and arrangement of the parts described without departing from the invention, and hence I do not wish to limit myself to the precise details set forth, but shall consider myself at liberty to make such slight 35 changes and alterations as fairly fall within the spirit and scope of the appended claims.

I claim:

40 1. A device of the character described, including a bag, a collapsible box fitting within the bag and including a bottom wall, a side wall, and an end wall, said bag adapted to collapse with the box.

45 2. A device of the character described, including a bag, a collapsible box fitting within the bottom of the bag, and side cover flaps on the box adherently connected to the inside of the bag.

50 3. A device of the character described, including a bag, a collapsible box fitting within the bottom of the bag, side cover flaps on the box adherently connected to the inside of the bag, and end flaps unconnected

to the bag adapted to be folded over to retain the box in open position for packing.

4. A device of the character stated, including a bag, a box on the bottom of the bag snugly fitting the bag side, and end cover flaps of the box adapted to lie against the inside of the bag when the box is open, said end flaps and the ends of the box being longitudinally scored from the top of the flaps to a point adjacent the bottom of the box, said box provided with diagonal score lines 65 extending from the lower end of said first mentioned score lines to the lower corners of the box, whereby said box is adapted to break inwardly at its ends, and means permitting lateral folding of the box when it 70 has been partially broken in.

5. A device of the character stated, including a bag, a box on the bottom of the bag snugly fitting the bag side, and end cover flaps of the box adapted to lie against the inside of the bag when the box is open, said end flaps and the ends of the box being longitudinally scored from the top of the flaps to a point adjacent the bottom of the box, said box provided with diagonal score 80 lines extending from the lower end of said first mentioned score lines to the lower corners of the box, whereby said box is adapted to break inwardly at its ends, said box formed with a horizontal score line encircling 85 the box and defining the lower ends of the vertical score lines, whereby said box body may be flatly folded upon the box bottom.

6. A device of the character described, including a bag, a collapsible box fitting within the bottom of the bag, side cover flaps on the box adherently connected to the inside of the bag, the mouth of said bag adapted to be folded over upon itself when said 95 flaps are closed, and means for locking the mouth in closed position.

7. A device of the character described, including a bag, a collapsible box fitting within the bottom of the bag, side cover flaps on the box adherently connected to the inside of the bag, the mouth of said bag adapted to be folded over upon itself when said flaps are closed, and means for locking the mouth in closed position, said means including 105 hooks engageable under the outside of the side flaps.

WILLIAM C. DEISS.
